UNITED STATES PATENT OFFICE.

GEORGE E. PANCOAST, OF BROOKLYN, NEW YORK, ASSIGNOR TO THE AMERICAN LITHOGRAPHIC COMPANY, A CORPORATION OF NEW YORK.

GRIPPER MECHANISM.

SPECIFICATION forming part of Letters Patent No. 747,213, dated December 15, 1903.

Application filed April 23, 1903. Serial No. 153,919. (No model.)

To all whom it may concern:

Be it known that I, GEORGE E. PANCOAST, a citizen of the United States, and a resident of Brooklyn, in the county of Kings and State 5 of New York, have invented certain new and useful Improvements in Gripper Mechanism, of which the following is a specification.

This invention relates to devices for gripping and carrying sheets of paper or similar 10 material, said devices being especially adapted for use in printing-presses or similar paper-manipulating machines. Devices of this character usually consist of a series of gripping-fingers constructed to move into and out 15 of contact with a relatively stationary member forming one edge of a cylindrical sheet-carrying surface, as the impression-surface of a printing-press. Much difficulty has been experienced in causing such a gripper as or- 20 dinarily constructed to take the sheets from a sheet-presenting device without the occurrence of more or less slipping between the sheet and the gripper and without the amount of the slip of successive sheets varying more 25 or less, so that all the sheets will not occupy the same position in the machine, as required—for instance, to secure accurate register of the impressions in multicolor-printing.

I have found that the slipping, or at least 30 the variations in the amount of the slip between the grippers and the sheets, is due in part to the fact that all the gripper-fingers do not begin to press on the edge of the paper at the same time and in part to the fact that 35 when wholly closed the gripper-fingers do not bear with equal force on the paper.

My invention has for an object, therefore, to provide a construction whereby the gripper-fingers may be adjusted with great nicety to 40 make pressure contact with the paper simultaneously and to rest thereon each with the same degree of pressure; also, to provide a construction which, nevertheless, is simple and cheap and which when once adjusted 45 will maintain its adjustments indefinitely. These and other objects of my invention will more fully appear from the following description.

My invention consists in the novel parts, im- 50 provements, and combinations herein shown and described.

The accompanying drawings, which are referred to herein and form a part hereof, illustrate one embodiment of my invention and serve in connection with the description herein to explain the principles thereof.

Of the drawings, Figure 1 is a sectional view illustrating a gripping device constructed in accordance with my invention as applied to a paper-carrying cylinder. Fig. 2 is 60 a sectional view, on an enlarged scale, through one of the gripper-fingers and its supporting-shaft; and Fig. 3 is a plan view, on the same scale as Fig. 1, of a portion of the gripper-shaft removed from the cylinder.

Like reference-numerals refer to like parts. A gripper constructed in accordance with my invention, broadly considered, comprises a relatively fixed member, a movable member, a device by which said movable member is 70 operated, a yielding connection between the movable member and its operating device, said connection being arranged to permit the movable member to yield with relation to its operating device in a direction away from 75 the fixed member, and adjustable means for positively fixing the position of said movable member in the opposite direction.

In accordance with the best embodiment 80 of my invention and, as shown in the drawings, the fixed member of the gripper consists of the forward edge of a sheet-carrying surface, the same consisting of the surface of a cylinder 1, fixed on a supporting-shaft 2. This cylinder may form the impression or 85 other sheet-carrying member of a printing-press. In accordance with the construction shown this cylinder is arranged to take the sheets from a feed-board 3, the sheets being fed with their forward edges against the 90 front stops 4, which are adapted to coöperate with the paper-guides 5 and 6. The movable member of the gripper consists of a series of gripper-fingers 7, and the operating device for the movable member also constitutes the 95 support thereof, the same, as shown, consisting of a rock-shaft 8, on which the gripper-fingers 7 are independently mounted in a row. The rock-shaft 8 is suitably journaled at its opposite ends, so as to lie in a transverse opening or gripper-gap 9 of the cylinder 1 in position for the free ends of the finger 7 to coöp-

erate with the surface of the cylinder along one edge of the gap. As the means for rocking the shaft 8 to move the grippers into and out of contact with the gripper edge on the 5 cylinder form no part of the present invention and are not necessary to a complete understanding thereof, they are not shown in the drawings and will not be described herein. The yielding connection between each 10 of the gripper-fingers and the rock-shaft 8, whereby the fingers are permitted to yield in one direction with relation to the shaft, may be formed in any suitable way, as may also the adjustable means for positively fixing 15 the position of the fingers with relation to the shaft in the opposite direction. In accordance with the construction shown each of the gripper-fingers is fitted to a suitable annular recess or groove 10 in the gripper-shaft, 20 the gripper-fingers being to facilitate their attachment and removal made in two parts, 7 and 11. The opening for the gripper-shaft 8 is formed between two parts 7 and 11, which parts are secured together and clamped 25 with a closed working fit onto the shaft 8 by means of the screws 12. In accordance with the best embodiment of the invention a recess 13 is formed between the grippers 7 and 11 at one side of the opening in which the 30 shaft 8 is located, and the shaft 8 is provided with a rigid abutment or arm 14, adapted to occupy an intermediate position in the recess 13. The arm 14 may be formed and secured to the shaft in any suitable way. As shown, 35 it is set into a slot or keyway formed in one side of the shaft 8 and is provided with a pin 15, which is fitted to an opening in the shaft and is riveted at the opposite side thereof. For the purpose of accurately adjusting and 40 at the same time positively fixing the position of the gripper with relation to the shaft 8 in a direction toward the gripper edge of the cylinder the part 11 of the gripper is provided with a set-screw 16, which projects through 45 one side of the recess 13 and into contact with the arm 14, a jam-nut 17 being provided to hold the set-screw 16 in its adjusted position. The yielding connection between the gripper 7 and its supporting-shaft 8, adapted to permit 50 the gripper to yield with relation to the shaft in a direction away from the gripper edge of the cylinder in accordance with the best embodiment of the invention and, as shown, consists of a block 18 of soft rubber or similar resilient material, which is confined between the arm 14 and a plate 19, fitted in the opposite side of the recess 13 from the adjusting-screw 16. To vary the compression of the block 18, the plate 19 may be adjusted in the 55 recess toward or away from the arm 14 by means of a set-screw 20. It follows from this construction that by manipulating the set-screw 16 all of the gripper-fingers may be so set with relation to the shaft 8 that they will 60 come into contact with the gripper edge of the cylinder, and thus into pressure-contact with the paper thereon at the same instant.

Then by manipulating the set-screws 20 the compression of the yielding or resilient connections 18 may be so adjusted that each of 70 the grippers will bear on the paper with the same amount of force, and these adjustments may be secured easily and with great accuracy.

My invention, in its broader aspects, is not 75 limited to the precise construction shown nor to the particular construction by which it may be carried into effect, as many changes may be made in the construction without departing from the main principles of the invention and without sacrificing its chief advantages.

Having thus described my invention, what I claim as new, and desire to secure by Letters Patent, is—

1. A gripper comprising a relatively fixed member, a movable member, a device by which said movable member is operated, a yielding connection between the movable member and its operating device, said connection being arranged to permit the movable member to yield with relation to its operating device in a direction away from the fixed member and adjustable means for positively fixing the position of said movable member 95 in the opposite direction with relation to its operating means.

2. A gripper comprising a relatively fixed member, a movable member, a device by which said movable member is supported and 100 operated, a yielding connection between the movable member and its support, said connection being arranged to permit the movable member to yield with relation to its support in a direction away from the fixed member 105 and adjustable means for positively fixing the position of said movable member in the opposite direction with relation to its support.

3. A gripper comprising a relatively fixed member, a movable member, a rock-shaft on 110 which said movable member is mounted, a yielding member between the movable member and said rock-shaft, said connection being arranged to permit the movable member to yield with relation to the rock-shaft in a direction away from the fixed member and adjustable means for positively fixing the position 115 of said movable member in the opposite direction with relation to the rock-shaft.

4. A gripper comprising a relatively fixed 120 member, a gripper-finger, a rock-shaft on which said gripper-finger is mounted, an arm fixed to said shaft, a pair of abutments on said gripper-finger between which said arm is confined, one of said abutments being adjustable 125 and a spring arranged between the other abutment and said arm.

5. A gripper comprising a relatively fixed member, a gripper-finger, a rock-shaft on 130 which said gripper is mounted, an arm fixed on said shaft, a pair of abutments on said gripper-finger between which said arm is confined, one of said abutments being adjustable, and a spring arranged between the other

- of said abutments and said arm, said adjustable abutment being arranged to oppose movement of the gripper-finger with relation to the rock-shaft in a direction toward the fixed member.
6. A gripper comprising a relatively fixed member, a gripper-finger, a rock-shaft on which said gripper-finger is mounted, an arm fixed on said shaft, a pair of adjustable abutments on said gripper-finger between which said arm is confined, and a spring arranged between one of said abutments and said arm.
7. A gripper comprising a relatively fixed member, a gripper-finger, a rock-shaft on which said gripper-finger is mounted, an arm fixed on said shaft, a pair of adjustable abutments on said gripper-finger between which said arm is confined, and a spring arranged between one of said abutments and said arm, said spring being arranged to oppose the movement of the gripper-fingers with relation to the rock-shaft in a direction away from the fixed member.
8. A gripper comprising a relatively fixed member, a gripper-finger, a rock-shaft having a groove in which said gripper-finger is confined, an arm fixed in the groove on said shaft, a recess in said gripper-finger in which said arm is confined, and a spring confined between said arm and one side of said recess.
9. A gripper comprising a relatively fixed member, a series of gripper-fingers, a rock-shaft on which said gripper-fingers are mounted, a series of arms fixed on said shaft, one for each of said gripper-fingers, a pair of adjustable abutments on each of said gripper-fingers between which abutments one of said arms is confined, and a series of springs, one arranged between each of the said arms and one of the abutments on each of the grippers.
10. A gripper comprising a relatively fixed member, a series of gripper-fingers, a rock-shaft having a series of grooves in which said gripper-fingers are confined, an arm fixed in each of the grooves on said rock-shaft, a recess in each of said gripper-fingers in which the corresponding arm is confined, and a block of resilient material confined between each of said arms and one side of the corresponding recess.
11. A gripper comprising a relatively fixed member, a series of gripper-fingers, a rock-shaft having grooves in which said gripper-fingers are confined, an arm fixed in each of said grooves on said rock-shaft, a recess in each of said gripper-fingers in which the corresponding arm is confined, and a block of yielding material confined between each of said arms and one side of the corresponding recess so as to oppose movement of the gripper-fingers relative to the rock-shaft in a direction away from said fixed member.
12. A gripper comprising a relatively fixed member, a series of gripper-fingers, a rock-shaft having grooves in which each of said grippers is confined, an arm fixed in each of said grooves on said rock-shaft, a recess in each of said gripper-fingers in which the corresponding arm is confined, a set-screw projecting into one side of each of said recesses and a block of yielding material confined between each of said arms and the other side of the corresponding recess.

In testimony whereof I have signed my name to this specification in the presence of two subscribing witnesses.
